Des. 195,663
Patented July 16, 1963

195,663

LIQUID DISPENSER

Siegfried H. A. Schmaus, Philadelphia, Pa., assignor to Ametek, Inc., a corporation of Delaware

Filed Mar. 21, 1960, Ser. No. 59,793

Term of patent 14 years

(Cl. D2—3)

Des. 195,663

PAGE 2

Fig. 3

Fig. 2

FIG. 1 is a front perspective view of a liquid dispenser showing the new design.

FIG. 2 is a side view thereof.

FIG. 3 is a rear perspective view thereof.

FIG. 4 is a top view.

The dominant features of my design reside in the portions shown in full lines.

I claim:

The ornamental design for a liquid dispenser, substantially as shown and described.
